wardly and downwardly to form a rim surrounding and spaced from the side walls, said rim being provided with key-hole slots at opposite sides and at points above the lower edge thereof, and a flat support on which said dish may rest, of a fastening device comprising an extensible and flexible member adapted to pass beneath said support, said member having at its ends anchoring means constructed to detachably engage in said key-hole slots.

2. The combination with a dish adapted to be supported on a chair tray, said dish having its peripheral portion rolled over and extending outwardly and downwardly substantially to the plane of the bottom of the dish to form a rim surrounding and spaced from the side walls, said rim being provided with openings at diametrically opposite points located wholly above its lower edge, of a fastening device comprising an extensible and flexible member wholly unconnected with said dish or tray, having at each end an anchoring element constructed to detachably engage directly in said openings, said member being of such length as to extend beneath and around the tray.

BERNARD A. SELTEN.
ELIZABETH SLATER.
